Application April 21, 1958, Serial No. 729,890

5 Claims. (Cl. 81—60)

The present invention relates to ratchet wrenches. More particularly it relates to ratchet wrenches adapted to drive an object offering low resistance to back-motion, and even more particularly it relates to a hand driven ratchet wrench adapted for use in confined quarters.

It is an object of this invention to provide an improved ratchet wrench of the character indicated.

It is a further object of this invention to provide a ratchet wrench which ratchets when operating on an object such as a threaded nut or bolt which is so free to advance or withdraw along its thread that it provides insufficient resistance against back motion to cause a conventional ratchet wrench to ratchet.

It is also an object of the present invention to provide a ratchet wrench which is capable of ratcheting and which will not reciprocate idly even when driving an object having no resistance against back motion.

Another object of this invention is the provision of a midget ratchet wrench which is suitable for use in closely confined quarters.

Yet another object of the invention is a ratchet wrench which is suitable for use by the fingers of one hand in confined quarters to drive helically threaded objects throughout a course of travel in at least part of which there is little or no resistance to back motion of the object being driven.

A further object of the invention is to provide such a wrench having a driven element located eccentrically in a circular driving handle, thereby providing a continuous finger-gripping surface and a minimum projection of the handle in one direction beyond the axis of the driven element.

A conventional ratchet wrench contains a pawl, click, detent, or similar locking member which in conjunction with a ratchet wheel or similar stepping mechanism provides positive drive in one direction and an escaping action in another. A spring or other biasing means urges the locking member against the ratchet wheel so as to secure positive ratcheting action. In order to overcome the effect of this biasing action and cause ratcheting to occur during the back or return stroke of the wrench, a force or torque sufficient to overcome the residual bias of the spring must be applied to the driven member of the wrench, or the driven member will follow the reciprocating action of the handle of the wrench. Thus, a conventional ratchet wrench normally will not ratchet when driving a nut along a threaded shaft until the nut has approached the limit of the unobstructed free thread and is subjected to sufficient frictional resistance to back motion to overcome the bias of the spring in the ratchet mechanism.

While in some instances this problem may be overcome by running a nut or screw along its thread by hand, until the limit of free travel is reached, or by using one hand to drive a ratchet wrench and another to hold the screw or nut (or the driven member of the wrench) so as to prevent back motion and cause ratcheting to occur, such methods are unsatisfactory in closely confined quarters where there may be barely room for one hand or a few fingers and where the nut or screw may have to be driven in a recessed opening.

The ratchet wrench of the present invention readily

overcomes these problems. In accordance with the present invention, a ratchet wrench adapted to drive an object offering low resistance to back motion and idle reciprocation comprises a handle, a driving member, ratchet means coupling said handle and said driving member, said ratchet means being biased against ratcheting, and frictional braking means coupled to said driving member and adapted to overcome said bias so as to restrain said driving member from free motion, thereby causing ratcheting to occur and preventing idle reciprocation of said driving member when driving an object lacking sufficient resistance to back motion to overcome said bias. The present wrench may be employed to drive a wide variety of sockets, tangs, e.g. screw drivers, bits and the like. The screw drivers, bits and the like may telescope within a socket and have stops thereon so that their length is adjustable as desired.

Other objects and advantages of the present invention will become apparent to those skilled in the art from a reading of the present specification in conjunction with the accompanying drawings, which constitute a presently preferred embodiment of the invention.

In the drawings:

Fig. 1 is a side elevation of a ratchet wrench constructed in accordance with the present invention and illustrated as applied to a socket;

Fig. 2 is a cross-sectional view taken in the plane 2—2 of Fig. 1 in the direction indicated;

Fig. 3 is a bottom view of the wrench of Fig. 1 with the finger ring 34 of Fig. 1 omitted for convenience of illustration.

Fig. 4 is an enlarged sectional view taken in the plane 4—4 of Fig. 1; and

Fig. 5 is an auxiliary lever handle which may be used in conjunction with the wrench of Fig. 1 to increase the torque applied thereto.

Referring to the drawings, a drive shaft 2 is journaled in and extends through a cylindrical body or handle 4 near the outer periphery thereof. The handle is knurled or ridged on its outer face so as to facilitate finger gripping.

The drive shaft 2 carries a toothed ratchet wheel 6 which is recessed within the handle 4. The teeth of the ratchet wheel engage a pawl 8 having two pairs of teeth 10, a recessed segment 12, and a dual track 14 cut on its periphery. The pawl is mounted on a pin 16 which extends through and is free to swivel in the body of the handle 4. Mounted on the upper end of the pin is a head 18 carrying an arm 20. A spring 22 urges a ball 24 into one half of the track in the periphery of the pawl, thereby providing a detent action.

As is apparent, rotation of the arm 20 serves to swivel the pawl 8 so as to change the portion of the track in which the ball 24 rides from one half thereof to the other, thereby reversing the direction in which the shaft 2 drives and ratchets.

The lower extremity of the shaft 2 is square in cross-section and is provided with a detent 25 so as to accept and hold conventional drive sockets. These sockets may be of any shape such as square, hexagonal, round, etc.

The upper extremity of the shaft 2 terminates in a ball 26. The ball is received in a clamp assembly 30 having a hollow socket clamp 32 at one end thereof and a finger ring 34 at the other end. The ball and the socket clamp constitute a swiveling friction brake as an integral part of the wrench, tension on the clamp being adjusted by means of a screw 35.

In use, a socket 36, shown in dotted outline in Fig. 1, is placed on the lower end of the drive shaft 2. The index finger of one hand is slipped through the finger ring 34 which is then held stationary by the finger. Alternatively any type of finger or hand grip such as a palm

ring can be used and reference to the finger ring includes such means. The knurled driving handle 4 is operated by the thumb and middle finger of the same hand.

During the drive stroke, i.e., clockwise rotation of the driving handle when the swivelling pawl is in the position illustrated in Fig. 4, the teeth of the ratchet wheel ride on the periphery of the pawl which is held in position by the influence of the spring-loaded ball 24 in the track 14. On the back or return stroke, i.e., counter-clockwise rotation of the driving handle when the swivelling pawl is in the position illustrated in Fig. 4, it is necessary to overcome the resistance of the spring 22 in order to cause the pawl to swivel the short distance (i.e., a portion of the half of the track in which the ball 24 is inserted) necessary to cause ratcheting to occur. (If this resistance is not overcome, the drive shaft will follow the driving handle as it is oscillated, and thus will reciprocate idly without ratcheting.)

The resistance necessary to accomplish ratcheting is transmitted to the drive shaft through the frictional braking assembly, i.e., the ball and socket clamp, from the finger which is inserted in the finger ring 34 and held stationary.

Thus, the ball slips in the stationary socket 32 and unidirectional positive coupling between the driving handle 4 and the drive shaft 2 is realized on the drive stroke. On the return stroke of the handle, contradirectional ratcheting of the drive shaft is accomplished even in the absence of any resistance to back motion on the part of the nut or screw being driven by the socket affixed to the wrench. This occurs because the frictional resistance to slippage of the ball 26 in the socket 32 of the stationary clamp assembly 30 is greater than and overcomes the bias of the spring 22, thus causing the pawl to compress the spring and swivel to permit ratcheting.

The finger ring and socket clamp assembly may be positioned perpendicular to the drive shaft 2 as illustrated, or may be set at any convenient or comfortable angle.

The driving handle 4 is provided with tapped recesses 38 (Figs. 2, 3 and 4) into which a threaded lever handle 40 (Fig. 5) may be inserted when space permits so as to avail of greater additional driving torque.

While there has been disclosed and illustrated that which is presently considered to be a preferred embodiment, it is apparent that variations may be made and equivalents substituted within the scope of this invention. Thus, although in the illustrated embodiment the drive shaft is eccentrically mounted within a cylindrical handle so as to realize greater torque in conjunction with diminished overhang and increase clearance on one side of the handle, it is clear that the drive shaft may be concentrically mounted within the handle, and that handles of non-cylindrical shape may be employed. It will also be apparent to those skilled in the art that a wide variety of frictional braking means may be substituted for the ball and socket joint presently illustrated, and that the "handle" referred to herein need not be a finger operated handle but may be any suitable drive means on which a force is exerted in any appropriate manner.

It will also be apparent that the integral braking principle of this invention may be applied to a wide variety of ratchets, however the present embodiment is considered especially desirable in view of the fact that it is readily operable by the fingers of only one hand and may be used in closely confined quarters. While the invention has been described with reference to one embodiment thereof as hereinbefore set forth, it is to be clearly understood that the invention is not limited thereto, but includes various modifications and equivalents within the scope of the appended claims.
